ACCELERATING PUMP

Harold A. Carlson, University City, Mo., assignor
to Carter Carburetor Corporation, St. Louis,
Mo., a corporation of Delaware

Application May 6, 1939, Serial No. 272,124

4 Claims. (Cl. 261—34)

This invention relates to internal combustion engine carburetors and more particularly to accelerating devices to be used in connection therewith.

5 Auxiliary fuel is injected into the air stream in present day carburetors during engine acceleration when sufficient fuel from aspirating nozzles cannot be obtained due to low air velocities through the carburetor or to low fuel levels in 10 the aspirating nozzles due to pull back by interconnected idling fuel passages.

15 This auxiliary fuel is usually referred to as accelerating discharge and is most commonly provided by a reciprocating plunger type accelerating device interconnected by link mechanism to the carburetor throttle and adapted to discharge into the main air passage through the carburetor upon opening movements of the throttle.

20 It is obvious that in an automotive-type engine driving a vehicle, the air velocity through the carburetor which immediately ensues upon an opening movement of the throttle from a near closed or idling position with a commensurate 25 engine speed, will be low as compared to the immediate resulting velocity following a throttle opening movement from say, a half open position with the normal corresponding engine speed. Also it is evident in the latter instance that fuel 30 will be flowing from the aspirating nozzle and that it possesses some momentum, whereas in the former instance an interval will be required to lift the fuel from some point below the point of discharge of the aspirating nozzle.

35 It has been found that in the operation of modern automotive internal combustion engines, this auxiliary fuel as supplied by an accelerating device is not required for throttle opening movements beyond a certain throttle open position. 40 For economical reasons it is, therefore, advantageous to provide a means of conserving the fuel during those throttle opening movements in which it is not required.

45 It is an object of this invention to provide an accelerating device of the above character in which means are provided for diverting the accelerating discharge from the air stream to the supply chamber during those throttle opening movements in which such auxiliary fuel is not required.

50 Other objects and advantages will appear upon referring to the following description and accompanying drawing in which

55 Fig. 1 is a diagrammatic representation of a carburetor embodying one form of my invention.

Fig. 2 is a fragmentary view of the carburetor shown in Fig. 1 embodying a modification of my invention.

Fig. 3 is also a fragmentary view of the carburetor shown in Fig. 1 embodying still another 5 modification of my invention.

Referring to Fig. 1, the reference numeral 1 indicates a main carburetor body member having a mixing conduit 2 formed therein. A constant level fuel chamber 3 also formed in the 10 main body member is provided and a constant level of fuel as indicated by the dot-dash line A—A is maintained therein by the float 4 and intake needle 5.

An air inlet casting 6 and an outlet casting 15 7 suitably attached to the main body member 1 are provided.

The air inlet 8 is controlled by a conventional plate-type choke valve 9 and the carburetor outlet 10 is controlled by a conventional plate-type 20 throttle valve 11 suitably attached for rotation with throttle shaft 12 as with screws 13.

Fuel for acceleration is supplied by an accelerating device comprising a cylindrical chamber 13 having a plunger 14 arranged for reciprocation 25 therein. Motion is imparted to the plunger 14 upon movement of the throttle valve by means of the plunger shaft 15, link 16, lever 17 which is pivoted at 18, link 19 and lever 20 which is rigidly attached to the throttle shaft 12. 30

Upon the intake or upward stroke of the plunger 14, fuel flows into the chamber 13 from the constant level chamber 3 through the valve controlled passage 21 around the spring retained combination intake and by-pass valve 22, fuel 35 passages 23 and 24 and opening 25.

On the downward or discharge stroke of the plunger 14 fuel is forced through opening 25, passage 26 around gravity discharge valve 27 through passages 28 and 29 and is discharged 40 into the mixing conduit and the air stream through discharge nozzle 30 and orifice 31.

In order to divert the fuel from the mixing conduit at a predetermined throttle position, I have provided the valve pin 31 which is guided 45 in the casting 6 and held normally in the position shown by the spring 32.

A lug 33 on lever 17 engages the pin 31 at some predetermined throttle position and any further opening movement of the throttle will cause pin 50 31 to be moved downwardly thereby forcing valve 22 downward and off its seat. The spring 34 which normally holds valve 22 on its seat is calibrated to permit the proper functioning of valve 22 as an intake check valve.

Passages 35 and 36 in the plunger shaft 15 are provided to relieve pressure in the chamber 13 which may result from vaporization of the fuel therein due to absorption of heat from surrounding engine parts and which would, if not relieved, cause untimely discharge of fuel into the mixing conduit. It will be understood that passage 36 in plunger shaft 15 is relatively small and the amount of fuel escaping therethrough during a discharge stroke is negligible.

A slot 37 in the wall 13 extending to a point below the level of fuel is provided to supply fuel to chamber 13 above the plunger 14 at all times thereby insuring a liquid seal for the plunger.

15 In the modification disclosed in Fig. 2 separate valves are provided for intake and by-pass control. Other associated elements similar to those shown in the device of Fig. 1 are indicated by similar numerals. The by-pass valve 38 in 20 this arrangement is provided with a vertically extending stem 39 which is engaged by the plunger 14 at some predetermined throttle position after which any further throttle opening movement will force valve 38 downward causing 25 the fuel to be by-passed back into the chamber 3, through openings 40 around valve 38 through passages 41, 42 and 43.

It will be understood that the spring 44 which normally urges valve 38 upward in engagement 30 with its seat may be calibrated to permit the opening of the valve by a predetermined fluid pressure before the plunger 14 contacts the valve stem 39.

This feature is found desirable when the device 35 is used in connection with certain automotive engines and carburetors.

Referring to Fig. 2 on the upward or intake stroke fuel enters chamber 13 from the constant level bowl 3 through passages 43 and 42 around 40 the gravity intake check 45 and through opening 46.

On the downward or discharge stroke fuel is discharged through opening 47, into the mixing conduit in a manner as previously described.

45 In the modification shown in Fig. 3 a by-pass valve 48 is provided and normally held in engagement with its seat in passage 49 through plunger 50 by the spring 51.

A standard or pin 52 rigidly positioned at the 50 bottom of chamber 13 forces valves 48 from its seat at a predetermined throttle position, permitting the fuel to be by-passed back into chamber 3 through passages 49 in plunger 50, passages 53 and 54 in plunger rod 55 and slot 37 in 55 the wall of chamber 13.

Fuel enters chamber 13 on the intake stroke through opening 56 around gravity intake check 45 and passage 46 and is discharged into the mixing conduit through similar passages as 60 shown in Figs. 1 and 2.

It will be understood that the orifice 57 in the discharge nozzle 30 is relatively small when compared with the net opening of the by-pass so that a relatively small amount of fuel is discharged therethrough after the by-pass valve is 65 opened.

In operation fuel is supplied to the carburetor through inlet passages 58 and 59 and a substantially constant level of fuel is maintained in the 70 chamber 3 by the float 4 and the needle 5.

Fuel for normal and high speed operation is supplied through orifice 60, passages 61, 62 and 63 and discharges into the mixing conduit at 64.

Fuel for idling or substantially closed throttle operation is supplied through orifice 65, passages 66, 67, restricting passage 68, passages 69, 70, 71, 72, 73, 74 and discharges near the edge of throttle plate 13 through port 75.

Upon throttle opening movements the accelerating device plunger is caused to move down 10 in a manner described thereby discharging fuel for acceleration into the mixing conduit. As the throttle reaches a predetermined point the bypass valve is positively opened and any further discharge from the accelerating chamber is diverted.

On closing movements of the throttle, fuel is drawn into the accelerating chamber from the constant level chamber by the upward movement of the plunger. The detailed drawings and 20 description are intended to be illustrative and not limiting, and the exclusive use of all modifications which come within the scope of the appended claims is contemplated.

I claim:

1. In a carburetor, a mixture conduit, a constant level fuel bowl, a throttle in said conduit, aspirating fuel passage means connecting said fuel bowl with said conduit, an accelerating pump including a movable part and a working 30 chamber, a passage connecting said working chamber with said fuel chamber and a more restricted discharge passage opening into said mixture conduit, a resiliently seated valve in said first-mentioned passage and an outwardly opening 35 check valve in said discharge passage, a positively operating connection between said throttle and the movable part of said pump, and means actuated by movement of said movable part to positively unseat the valve in said connecting 40 passage in coordination with discharging movement of said pump beyond a predetermined point whereby substantially the remainder of the pumped fuel is by-passed through said connecting 45 passage.

2. A carburetor as specified in claim 1 in which said connecting passage constitutes the sole inlet connection between the pump and said fuel chamber, the valve therein being responsive to charging movement of said pump for admitting 50 fuel to the pump.

3. A carburetor as specified in claim 1 including at least two passages connecting said working chamber with said fuel chamber, there being a pressure responsive valve in one of said passages operable upon charging movement of said pump movable part to admit fuel to said working chamber, said resiliently seated valve being located in a second one of said connecting 55 passages.

4. A carburetor as specified in claim 1 in which said connecting passage extends through said pump movable part, there being additionally provided a fixed abutment projecting from a wall of said working chamber positioned to be engaged by said resiliently seated valve for unseating the same.

HAROLD A. CARLSON.
